EDWARD P. DONNELLAN, OF BROOKLYN, NEW YORK, ASSIGNOR TO STANDARD-JOHNSON COMPANY, INC., OF BROOKLYN, NEW YORK, A CORPORATION OF NEW YORK

COIN GUIDING AND WRAPPER HOLDING MEANS FOR COIN COUNTING MACHINES

Application filed April 28, 1931. Serial No. 533,400.

This application is a continuation in part of my copending application Ser. No. 408,187, filed November 19th, 1929; and the same relates to improvements in coin guiding and 5 wrapper holding means for coin counting machines.

This invention has for its principal object to provide, for use in connection with coin counting machines having means to separate 10 coins of different denominations and deliver the separated coins respectively to counting mechanism for given corresponding denominations, a novel arrangement and construction of means to removably hold 15 tubular wrappers corresponding to the different denominations of coins subject to the deposit therein of counted coins discharged from the counting mechanism, together with guide means to lead said discharged coins to 20 the thus held wrappers.

This invention has for another object to provide a novel coin guiding and wrapper holding means adapted to be detachably connected with the coin counting machine served 25 thereby.

Other objects of this invention, not at this time more particularly enumerated, will be understood from the following detailed description of the same.

An illustrative embodiment of this invention is shown on the accompanying drawings, in which:—

Fig. 1 is in part a side elevation and in part a vertical sectional view of a coin counting machine equipped with the novel coin guiding and wrapper holding means of this invention; and Fig. 2 is in part a front elevation and in part a transverse vertical section, taken on line 2—2 in said Fig. 1.

Similar characters of reference are employed in the above described views, to indicate corresponding parts.

Referring to said drawings, the reference character 10 indicates a suitable support or standard upon which the coin separating and counting mechanisms are mounted. The coin separating mechanism operates to deliver coins from the hopper 11 thereof through the usual graduated drop out opening 12 thereof, which functions to discharge coins of

different denominations according to their various diametric dimensions for downward movement through a properly corresponding chute-like passage of a series of chute-like passages 13, 14, 15, 16 and 17, respectively 55 adapted to receive dimes, pennies, nickels, quarters and half dollars. These chute-like passages are formed in connection with a transverse back-plate 18 extending between the sides of the support 10. 60

Connected with and forwardly projecting from the sides of the support 10 is a housing 19 adapted to contain the coin counting registers (not shown), which correspond in number to the number of denominations of 65 coins the machine is arranged to operate with. Each coin counting register is provided with an actuating shaft 20 having a coin engageable star wheel 21 for operating the same. The star wheels 21 respectively 70 lie in the path of the coins moving through the respective chute-like passages 13 to 17 inclusive.

Cooperating with each chute-like passage 13 to 17 inclusive, and located adjacent to 75 said star-wheel 21 are suitably driven propelling rolls 22, which are adapted to engage coins passing through said chute-like passages so as to positively force the same past the star-wheels 21 with actuating effect 80 upon the latter, and through the same upon the operating shafts 20 of the coin counting registers. Suitable means for stopping the machine when a given predetermined number of coins of any denomination have been 85 counted and registered, such, for example, as the means shown and described for such purpose in my said copending application Ser. No. 408,187.

The novel means for removably supporting tubular paper coin wrappers 23 and for guiding coins thereinto which are discharged from said chute-like passages 13 to 17 inclusive, after the same have actuated a proper coin counting register, comprises the following structure. 95

A detachable carrier-frame is provided, the same comprising a back wall 24, bottom wall 25 and side walls 26; the carrier-frame thus formed thereby being open at the front. Said 100

side walls 26 are provided on their exterior sides with hanger flanges 27 which are removably slidable in holding channels or ways 28 formed in the inner faces of sides of said 5 housing 19. Pivotsly mounted on the exterior faces of said side walls 26, below the hanger flanges 27, are locking eccentrics 28', which serve, when manipulated, to bind the hanger flanges 27 in the holding channels 10 or ways 28, thus firmly and securely retaining the carrier-frame against displacement from its operative assembled relation to the coin counting machine.

Provided in connection with the upper portion of the back wall 24 of said carrier-frame 15 are chute-like passages 13', 14', 15', 16' and 17' to respectively align and communicate with the lower ends of the corresponding chute-like passages 13, 14, 15, 16 and 17 of 20 the coin counting machine, thus forming extensions of the latter, and serving to guide counted coins discharged therefrom to the properly corresponding coin wrappers supported in and by the carrier-frame by the 25 means and in the manner about to be described.

Formed in connection with said back wall 24, at the lower ends respectively of the chute-like passages 13' to 17' inclusive, are rearwardly off-set wrapper seating sockets 29 of substantially semi-circular internal cross sectional shape and respectively sized to conform to the dimensions of the wrappers 23 to be served thereby. The rearwardly off-set relation of said seating sockets 29 provide stop shoulders 30 to determine the seated relation of the wrappers in connection with the chute-like passages 13' to 17' inclusive. Cooperative with said sockets 29 are socket cover 30 portions 31 of outwardly bowed semi-circular contour and of curvilinear internal conformation, so as to provide at their upper or top portions funnel-like coin receiving mouths 32, and so as to provide at their lower or bottom portions bell-shaped receiving sockets 33 to receive insertion of the upper open ends of the tubular wrappers 23, whereby said ends are guided toward and brought into stopped engagement with the stop shoulders 30. Said socket cover portions 31 are preferably formed in connection with a carrying bar 34, which is secured in assembled relation to the body or boss 35 in which the wrapper seating sockets 29 are formed by means 55 of fastening screws 36 or other suitable fastening means.

To removably hold the tubular wrappers 23 in the wrapper seating sockets 29 and stopped against the stop shoulders 30, while 60 at the same time closing the bottom ends of said wrappers in support of coins delivered thereto, spring-pressed plungers 37 are provided. These plungers are slidably movable through the bottom wall 25 of the carrier frame. Secured upon the upper ends of said

plungers are plugs 38 adapted to enter and fit within the lower ends of the wrappers 23, said plugs 38 having annular flanges 39 at their lower ends to engage and thrust upon the lower end of engaged wrappers 23. The 70 plungers 37 and their flanged plugs 38 are yieldably and upwardly biased by springs 40 which surround the plungers between the carrier frame bottom wall 25 and the flanged plugs 38. The lower ends of said plungers, which project beneath the carrier frame bottom wall 25, are provided with finger pieces 41 for retracting the plungers to permit insertion or removal of wrappers as necessary. 80

Pivotsly connected with the upper end portions of the sides of the carrier frame is a cover plate 42 adapted to normally overlie and cover the chute-like passages 13' to 17' inclusive. At the lower exterior portion of said cover plate 42 is affixed a finger piece 43 for manipulating the same. A spring clip 44 is fixed to the carrying bar 34 to frictionally engage the free end of said cover plate so as to normally retain the same in its closed position. It will be obvious that said cover plate may be raised at will to give access to the interior of said chute-like passages 13' to 17' inclusive should necessity arise. Normally the cover-plate closes the open front sides of 95 said chute-like passages against abnormal escape of coins passing therethrough.

Preparatory to operation of the machine, the tubular wrappers 23 for the different denominations of coin are inserted in proper positions in the carrier frame so that their upper open ends are held in registration with properly corresponding chute-like passages 13' to 17' inclusive. The lower ends of the wrappers 23 are annularly crimped to form 100 a stop bead 23' to retain the coins within the wrapper. 105

When any particular wrapper receives its quota of counted coins, the machine through the functioning of its clutch release mechanism of the general kind described in my aforesaid copending application Ser. No. 408,187, is stopped, whereupon the operator removes the filled wrapper by pulling down the plunger 37 to release its open end from the engaged wrapper seating socket 29 and stop shoulder 30, thereupon lifting the filled wrapper off of the engaged plug 38, and then turning in the open wrapper end in holding 110 engagement with the stack of coins therein. 115

A new wrapper is replaced for the thus removed filled wrapper, and the machine is again started until another wrapper is filled, whereupon the operations are repeated, etc. 120

As many changes could be made in the above construction and many apparently widely different embodiments of this invention could be made without departing from the scope thereof, it is intended that all mat- 125 130

ter contained in the above description or shown in the accompanying drawings shall be interpreted as illustrative and not in a limiting sense.

5 I claim:-

1. A tubular wrapper holding means for coin counting machines, comprising a carrier frame, means to detachably connect said carrier frame to the machine, said carrier frame having guide chute means to receive counted coins discharged by the machine, wrapper seating means aligned with said guide chute means, said seating means being offset relative to said chute means to provide a stop shoulder at the juncture thereof engageable by upper open ends of wrappers disposed in said seating means, and a spring biased retractable means to engage lower ends of the thus disposed wrappers to releasably retain the upper ends thereof engaged with said stop shoulder.

2. A tubular wrapper holding means for coin counting machines, comprising a carrier frame, said carrier frame having a series of passageways in its upper portion corresponding to and adapted to receive counted coins of different denominations discharged by the machine, a wrapper supporting seating means aligned with each passageway, said seating means being laterally off-set relative to said passageways, to provide stop shoulders to engage and position the open ends of inserted wrappers in registration with the cooperating passageways, and spring biased retractable means aligned with each seating means to engage the lower end of inserted wrappers to releasably retain the same in place, said latter means each having a plug to enter the lower end of an engaged wrapper to space entered coins from the lower extremity of the latter and also having a lateral annular flange to support the lower extremity of said wrapper.

3. A tubular wrapper holding means for coin counting machines, comprising a carrier frame, said carrier frame having a series of passageways in its upper portion corresponding to and adapted to receive counted coins of different denominations discharged by the machine, wrapper seating means having vertical seating channels of semi-circular cross section aligned respectively with said respective passageways and off-set relative thereto to provide a stop-shoulder to engage the upper ends of wrappers inserted therein, outwardly bowed semi-circular cover members fixed across the upper ends of said seating channels and forming with the latter circular sockets to embrace the upper ends of inserted wrappers, said seating channels and cover members being correspondingly sized according to the diameters of wrappers for coins of different denominations, and spring biased retractable plungers having plugs to enter the lower ends of seated wrappers, said plugs

having annular flanges to support the lower extremity of engaged wrappers.

4. A tubular wrapper holding means as defined in claim 2, in which said carrier frame is provided with a displaceable cover-plate to normally close over said chute-like passages.

5. A tubular wrapper holding means as defined in claim 3, in which said carrier frame is provided with a displaceable cover plate to normally close over said chute-like passages.

6. A tubular wrapper holding means as defined in claim 2, in which the carrier frame is provided with means for detachably connecting the same with a coin counting machine to be served thereby.

7. A tubular wrapper holding means as defined in claim 3, in which the carrier frame is provided with means for detachably connecting the same with a coin counting machine to be served thereby.

In testimony that I claim the invention set forth above I have hereunto set my hand this 20th day of April, 1931.

EDWARD P. DONNELLAN.
